DESIGN FOR A GRINDING MACHINE

Donald F. Price, Harold E. Balsiger, and Milburn A. Hollengreen, Waynesboro, Pa., assignors to Landis Tool Company, Waynesboro, Pa.

Application October 27, 1944, Serial No. 116,004

Term of patent 14 years

(Cl. D37—1)

To all whom it may concern:

Be it known that we, Donald F. Price, Harold E. Balsiger, and Milburn A. Hollengreen, citizens of the United States of America, residing at Waynesboro, in the county of Franklin and State of Pennsylvania, have invented a new, original, and ornamental Design for a Grinding Machine, of which the following is a specification, reference being had to the accompanying drawing, forming part thereof.

Figure 1 is a front perspective view of a grinding machine showing our new design; and Figure 2 is a rear perspective view thereof.

We claim:

The ornamental design for a grinding machine, substantially as shown.
